UNITED STATES PATENT OFFICE.

J. J. PARKER, OF MARIETTA, OHIO.

IMPROVEMENT IN PACKINGS FOR DEEP-WELL TUBES.

Specification forming part of Letters Patent No. **58,468**, dated October 2, 1866.

To all whom it may concern:

Be it known that I, J. J. PARKER, of Marietta, Ohio, have invented a new and useful Packing for Oil-Well; and I do hereby declare that the following is a full, clear, and exact description of the same, reference being had to the annexed drawings, making part of this specification, in which—

Figure 1 is a longitudinal vertical section; Fig. 2, a side view; and Fig. 3, a longitudinal vertical section of a part of the machine.

The nature of this invention consists in closing the space between the sides of a deep well and the tubing thereof by means of a bag consisting of double concentric tubing, fitted in the aforesaid space and made to expand to the required degree by hydraulic pressure.

This adjustable hydraulic packing is made as follows: I take two pieces of gum, leather, or other flexible tubing of the same length, but of different diameters, so that one may be placed within the other. The diameter of the exterior of these flexible tubes is nearly equal to that of the well to be packed, and that of the interior one is slightly greater than the diameter of the pump-tubing over which it is placed. The arrangement of all these tubes is seen at A B, Fig. 1.

C is a leather band, inserted at each end between the two bags or flexible tubes, holding them slightly apart. Inside the inner bag, at each end, is inserted a metallic ring about two inches in width, and large enough to slip easily over the joints of the pump-tubing. The ends of the flexible tubes are securely tied or wired over the exterior of said rings, and thus a cylindrical bag is made, perfectly watertight under heavy pressure.

D is a circular sheet of metal, perforated with holes and placed between the flexible tubes, extending from one of the leather bands above mentioned to the other, for the purpose of keeping the flexible tubes upright while being adjusted, and to prevent them from becoming lodged in the well.

E is a piece of tubing inserted between the upper ends of the bags, extending inside just below the leather band C, and outside about four or five inches. A shoulder, k, is formed upon this tube, just above the top of the packing-bag, to serve as a seat for a sleeve, F, slipped

over it, which sleeve has a pin, g, running through it, working in a slot, m, in the tube E, so that the sleeve can be lifted up an inch or more, for a purpose hereinafter described. A spiral spring holds the said sleeve firmly upon its seat. In the sleeve, at the top of the inner tube, E, small holes n are made, and covered with an elastic band, H, which acts as a safety-valve for preventing too much pressure being exerted upon the packing-bag.

The operation of the machine is as follows: The packing-bag is placed upon the pump-tubing and let down by means of a supply-pipe attached to the sleeve and extending to the top of the well. Water is introduced into the packing-bag by means of the aforesaid supply-pipe, and the pressure thereof in the bag is regulated by the safety-valve H, as above described. By this pressure the outer tube is forced tightly against the sides of the well, and the inner one is forced as firmly against the outside of the well-tubing, and the passage of water below the packing is thus entirely prevented. The pressure is removed from the interior of the packing-bag by lifting the supply-pipe and sleeve F, and opening a passage for the water through the slot m.

A similar packing-bag may be placed below the valve-chamber of the pump, upon a prolongation of the pump-tubing, closed at its lower end and perforated at the upper end, between the two packing-bags, for the purpose of allowing water and oil to enter. This lower bag must be connected with the upper one by pipes, through which the required pressure may be communicated. A vacuum may thus be created by the action of the pump in the space between the two bags, which may be lengthened or shortened at pleasure, if the connecting-pipe is made of flexible material capable of being coiled up and elongated.

By this method of packing deep wells every foot of the interior surface thereof may be subjected to a suction powerful enough to thoroughly test them. The amount of tubing in the well may also be increased or diminished at pleasure without taking it all out, a thing which is necessary to be done when the present general mode of seed-bagging is adopted. By this device, also, the necessity of ream-

ing out wells is done away with, as it can be readily adjusted to the sides of the well, no matter how rough they may be.

What I claim as my invention, and desire to secure by Letters Patent, is—

1. The sleeve F, pin g, and slot m, in combination with the safety-band H, in the manner described.

2. The outer and inner tubes, A B, the bands

C, and the inner metallic sheet D, in combination with the tube E, in the manner and for the purpose described.

This specification signed and witnessed this 29th day of February, 1866.

J. J. PARKER.
